CLAIM

The ornamental design for a snowflake microphone, as shown and described.

DESCRIPTION

FIG. 1 is a perspective view of a snowflake microphone showing our new design;

FIG. 2 is a perspective view thereof, shown without the base;

FIG. 3 is a top plan view of FIG. 2;

FIG. 4 is a side view of FIG. 2;

FIG. 5 is a back view of FIG. 2;

FIG. 6 is a bottom plan view of FIG. 2;

FIG. 7 is a front view of FIG. 2;

FIG. 8 is a perspective view of FIG. 2, shown in an open condition;

FIG. 9 is a top plan view of FIG. 8;

FIG. 10 is a side view of FIG. 8;

FIG. 11 is a front view of FIG. 8;

FIG. 12 is a bottom plan view of FIG. 8;

FIG. 13 is a back view of FIG. 8;

FIG. 14 is a perspective view of the snowflake microphone base;

FIG. 15 is a top plan view of FIG. 14;

FIG. 16 is a side view of FIG. 14;

FIG. 17 is a back view of FIG. 14;

FIG. 18 is a bottom plan view of FIG. 14; and,

FIG. 19 is a front view of FIG. 14.
